NEWTON N. BROWN, OF RACINE, WISCONSIN, ASSIGNOR TO GOLD MEDAL CAMP FURNITURE CO., OF RACINE, WISCONSIN, A CORPORATION OF WISCONSIN

FOLDABLE BED

Application filed June 21, 1926. Serial No. 117,333.

This invention relates to improvements in foldable beds.

One of the objects of the present invention is to provide an improved bed of the character referred to which is simple in construction, strong and rigid, which may be readily set up and folded into a compact bundle for transportation, and which may be manufactured at a relatively small cost.

Other objects and advantages will herein-after appear.

For the purpose of illustrating the invention, one embodiment thereof is shown in the drawings, in which

15 Figure 1 is a perspective view showing the improved bed set up, some of the parts being broken away for the sake of clearness;

Fig. 2 is an enlarged side elevational view of the improved bed when set up;

20 Fig. 3 is an enlarged sectional view, taken on the line 3—3 in Fig. 2;

Fig. 4 is an enlarged sectional view, taken on the line 4—4 in Fig. 2;

Fig. 5 is an enlarged sectional view, taken 25 on the line 5—5 in Fig. 2;

Fig. 6 is an enlarged sectional view, taken on the line 6—6 in Fig. 1;

Fig. 7 is a side elevational view, showing the improved bed partly folded;

30 Fig. 8 is a view similar to Fig. 7, showing the bed more completely folded;

Fig. 9 is an elevational view, looking toward the left in Fig. 8;

Fig. 10 is an enlarged end elevational view 35 of the bed frame completely folded, the mattress being laid out preparatory to wrapping of the same about the folded frame; and

Fig. 11 is a view similar to Fig. 10, showing the mattress wrapped about the folded frame.

40 The improved bed comprises the side members 10 and 11 jointed intermediate their respective ends for folding, as shown in Figs. 7 and 8, and the end members 12 and 13 pivotally connected at their ends to the respective ends of the side members by means of bolts or rivets 14. The side member 10 comprises the pair of complementary channel members 15 and 16, the end 17 of member 16 overlapping and nesting with the adjacent 45 end 18 of member 15 when these members are

moved into alignment, as shown in Figs. 1, 2 and 4, the respective flanges 19 and 20 of members 15 and 16 extending downwardly when the bed frame is set up, as shown. Hinged parts 21 are arranged between flanges 19 of channel member 15 and secured thereto by rivets 22, these parts being provided with apertured ears 23 extending outwardly beyond the edges of flanges 19. Similar and oppositely-directed hinge parts 24 are arranged between and secured to flanges 20 of channel member 16 by means of rivets 25 and are provided with apertured ears 26 which extend outwardly beyond the edges of flanges 20 and which register with the ears 23. A rivet 27 is passed through the registering apertures in ears 23 and 26 and provides a pivotal connection between the channel members 15 and 16, a spacing collar 28 being arranged on the rivet between ears 23, as shown in Fig. 5.

45 A supporting leg 29 of angle iron is arranged with its upper end fitted between flanges 19 of channel member 15 and is pivotally connected to the latter at a point removed from the outer end thereof by means of the rivet or bolt 30 whereby the leg may be folded upon member 15 and disposed between flanges 19 thereof throughout its entire length, as indicated in Fig. 8. For the purpose of holding leg 29 in supporting position a rigid brace 31 is pivotally connected at one end thereof to leg 29 by the rivet 32, the other end of the brace being hooked over a screw 33 screwed into the inner edge of end member 12 with its head spaced slightly therefrom to permit of insertion of this end of brace 31 between the screw head and member 12, as shown in Figs. 2 and 6. A jointed bracing element 34, comprising the parts 35 and 36, is pivotally connected at their adjacent ends by the rivet 37, is pivotally connected to channel member 15 and leg 29 by the rivets 38 and 39. The part 35 is provided with the laterally extending lug 40 arranged to enter the recess 41 in part 36 to prevent relative pivotal movement of these parts in one direction beyond the position thereof where they are in alignment to brace leg 29, as shown in Figs. 1 and 2. When it is desired to fold 50

leg 29, the brace 31 is unhooked from the screw 33 and swung downwardly about rivet 32 as a center into alignment with leg 29, as shown in Fig. 7 and in dotted lines in Fig. 6.

- 5 The bracing element 34 is then broken at its joint, as shown in Fig. 7, and leg 29 folded inwardly upon member 15 and between flanges 19 thereof, the arrangement being such that leg 29 and the brace 31 carried thereby 10 are disposed entirely between flanges 19, the bracing element 34 folding between member 15 and leg 29 at this time.

A leg 42, similar in construction to leg 29, is fitted at its upper end between the flanges 15 20 of channel member 16 and is pivotally connected to the latter at a point removed from its outer end by means of the rivet or bolt 43. The leg 42 is held in supporting position by means of the jointed bracing element 44 pivotally connected by means of rivets 45 to member 16 and leg 42 and which is similar in construction to the bracing element 34, and a rigid brace 46 similar in construction to the brace 31 and pivotally connected by the 25 rivet 47 to leg 42 and hooked at its upper end over the screw 48 screwed partly into the inner edge of end member 13 with its head spaced therefrom, as shown in Fig. 9, to accommodate the hook end of brace 46.

- 30 The side member 11 is identical in construction to side member 10, and comprises the channel members 49 and 50 pivotally connected at their adjacent inner ends by the rivet 51. A leg 52 similar to legs 29 and 42 35 is fitted at its upper end between the flanges of channel member 50 and is pivotally connected to the latter at a point remote from its outer end in the same manner as legs 29 and 42 are pivotally connected to the corresponding ends of channel members 15 and 16, leg 52 being provided with the rigid brace 53, similar in construction and manner of operation to braces 31 and 46, and the jointed bracing element 54 is similar in construction and 40 manner of operation to the jointed bracing elements 34 and 44. A leg 55, similar to legs 29, 42 and 52, is fitted at its upper end between the flanges of channel member 49 and is pivotally connected to the latter at a point 45 removed from its outer end in the same manner as legs 29, 42 and 52 are pivotally connected to channel members 15, 16 and 50 at points removed from their respective outer ends. Leg 55 is provided with the rigid brace 56 and the jointed bracing element 57 similar 50 in construction and manner of operation respectively to braces 31, 46 and 53 and the jointed bracing elements 34, 44 and 54.

- A spring mattress 58 of any suitable construction is provided at one end with an end member 59 secured to the end frame member 12 by screws 60, the outer edge 61 of member 59 being bent downwardly over the outer edge of member 12 to provide for a better connection between these parts and to relieve

71 screws 60 from unnecessary strain when the bed is set up and the mattress placed under tension in the manner hereinafter explained. The other end of mattress 58 is provided with the end member 62 which is co-extensive with the end frame member 13 and which is substantially U-shape in cross-section, as shown, member 62 being detachable with respect to member 13 and arranged to fit around the outer edge of the latter to connect this end 76 of the mattress thereto.

In setting up the bed, the side frame members 10 and 11 are unfolded, as shown in Figs. 1 and 2, and the legs 29, 42, 52 and 55 unfolded to their respective supporting positions 80 and the rigid braces 31, 46, 53 and 56 hooked to the end frame members 12 and 13 in the manner explained above. The jointed side frame members 10 and 11 are then broken a slight amount at their respective joints and the U-shape member 62 hooked over the outer edge of end frame member 13, after which the side frame members 10 and 11 are again straightened out as shown in Figs. 1 and 2, this action operating to pull the mattress 58 85 taut and place the same under tension. In this connection it is to be noted that since the pivotal connections 27 and 51 are below the mattress 58, the tension in the latter when the bed is set up has no tendency to cause side 90 members 10 and 11 to fold up, but on the contrary tends to keep them in operative position.

95 In folding up the bed, the side frame members 10 and 11 are first broken at their respective joints, and the U-shape member 62 then unhooked from end frame member 13 and the mattress 58 swung over to the left out of the way, as shown in Fig. 7. The rigid braces 31, 46, 53 and 56 are then unhooked from end 100 members 12 and 13 and swung downwardly into alignment with their respective legs 29, 42, 52 and 55, after which the jointed bracing elements 34, 44, 54 and 57 are broken, as shown in Fig. 7, and the legs folded inwardly 105 between the flanges of the channel members comprising side frame members 10 and 11. The folding of side members 10 and 11 is then completed, as shown in Fig. 8, and the folded side members then swung downwardly and 110 folded one upon the other between frame members 12 and 13, as shown in Figs. 9 to 11, after which the mattress 58 is wrapped about the folded bed frame, as shown in Fig. 11.

115 The nesting of the adjacent ends of channel members 15, 16, 49 and 50 when the bed is set up provides for great rigidity of the side frame members 10 and 11 and prevents spreading of the latter at their joints.

120 From the foregoing it will be seen that an improved bed has been provided which is simple in construction, which is rigid and durable, and which may be readily set up and folded into a compact bundle for transportation.

For the purpose of illustrating the invention one embodiment thereof has been shown and described, but of course various changes may be made such as in the size, shape and arrangement of the parts without departing from the spirit of the invention or the scope of the claims.

The invention claimed is:

1. A foldable bed comprising end rails, 10 side rails, each side rail comprising a pair of channel sections, the adjacent ends of the channel section of each side rail being pivotally connected together about a horizontal axis, the remote ends of the channel sections 15 of each side rail being directly engaged with and pivotally connected to the end rails about a vertical axis, the sections of each side rail being foldable up against each other about their horizontal axes and being foldable 20 down between the end rails about their vertical axes, foldable legs and braces connected to the side rails and adapted to be positioned within the channels thereof when the bed is folded up, the openings of the channels con- 25 fronting when the side rails are folded up whereby to maintain the folded legs and braces within the channel, the end rails serv- ing to maintain the engaging relation of the channel sections and the retention of the fold- 30 ed legs and braces therein when the bed is folded up.

2. A foldable bed comprising end rails, side rails, each side rail comprising a pair of channel sections, a hinge between the adja- 35 cent ends of each pair of channel sections, each hinge having a horizontal pivot offset below the sections of its side rails in the ex- tended position thereof, the remote ends of the sections of each side rail being pivotally 40 connected to the end rails about a vertical axis, foldable legs and braces connected to the side rails and positionable in the channels of the sections thereof when the bed is folded up, and a rollable spring having one end con- 45 nected to one end rail and its other end de- tachably connected to the other end rail, the channel sections of the side rail holding the foldable legs and braces within and between themselves in the folded position of the bed, 50 the end rails holding the folded side rails be- tween themselves and in folded position when the bed is folded up, the spring being rolled around the end rails to maintain the folded arrangement of these parts when the bed is 55 folded up.

In witness whereof, I hereto affix my sig- nature.

NEWTON N. BROWN.
